ULTRA HIGH FREQUENCY ELECTRIC
DISCHARGE DEVICEAnatole M. Gurewitsch, Schenectady, N. Y., as-
signor to General Electric Company, a corpora-
tion of New York

Application December 31, 1942, Serial No. 470,758

1 Claim. (Cl. 250—27.5)

1

My invention relates to ultra high frequency electric discharge devices and more particularly to ultra high frequency discharge devices of the magnetron type.

In the prior art electric discharge devices of the magnetron type applicable to the ultra high frequency range, the power output obtainable has been seriously limited by virtue of the configuration of the electrode elements and by the manner in which the interchange of energy between the space resonant regions or cavities and the space charge has been effected. In accordance with the teachings of my invention described hereinafter, I provide new and improved ultra high frequency magnetrons and methods of operating such devices wherein more effective utilization of the energy of the space charge is obtained.

It is an object of my invention to provide new and improved ultra high frequency electric discharge devices.

It is another object of my invention to provide new and improved ultra high frequency electric discharge devices of the magnetron type wherein electron-permeable or pervious anode structures are provided so that electrons having relatively large radial paths are effectively employed to obtain the desired transfer of energy between the field of the anode structures and the electrons constituting the rotating space charge.

It is a further object of my invention to provide a new and improved ultra high frequency magnetron wherein an electron-permeable anode structure establishes an electromagnetic field pattern, and which permits the passage of the electron space charge therethrough and wherein the electrons of the space charge undergo cyclic variations in velocity for effecting interchange of energy between the field of the anode structure and the space charge.

It is a still further object of my invention to provide new and improved methods of operating ultra high frequency magnetrons.

Briefly stated, in one of the illustrated embodiments of my invention I provide an ultra high frequency discharge device of the magnetron type wherein a space-resonant hollow anode member, having an opening facing a thermionic cathode, is employed for effecting interchange of energy between the space charge and the electromagnetic field established within the hollow anode member. The hollow anode member may have a U-shaped cross section and by virtue of its dimensions is susceptible of a predetermined mode of electrical oscillation, establishing there-

2

by a predetermined electromagnetic field pattern or a predetermined number of field patterns. A generally spiral motion is imparted to the electrons constituting the space charge, and the fields are so correlated that the electrons traverse paths of appreciable radii extending into the hollow anode region cooperating with the electromagnetic fields, or field patterns, to effect transfer of high frequency energy to the anode field, or derive energy therefrom. In such travel, within the electron-permeable anode region the electrons undergo substantial cyclic variations in velocity, supplying energy to, or deriving energy from, the field depending upon the purpose for which the discharge device as a whole is employed.

In accordance with one aspect of my invention, where the anode structure is of the above described hollow type, the dimensions of the hollow anode member may be chosen so that the energy-delivering electrons are outside the effective range of the anode region when the phase of the electrons relative to the electromagnetic field pattern changes to a point where these electrons would tend to absorb energy from the field or to deliver energy to the field, depending upon whether the device is employed for the production or utilization of the ultra high frequency energy.

In accordance with another embodiment of my invention, I provide an ultra high frequency magnetron wherein the anode structure comprises a plurality of spaced wafer-like metallic disks which are placed in alignment, and each of which includes an enlarged central opening and a plurality of circumferentially spaced, space-resonant regions or cavities in communication with the associated central opening. By virtue of the spaces between the various disks, there is provided an arrangement for permitting substantial rotational motion of the electrons constituting the space charge between the various disks, so that the kinetic energy of the oscillating electrons may be more efficiently utilized.

In accordance with a still further modification of my invention, I provide an ultra high frequency magnetron wherein the anode structure comprises a metallic annular member provided with a plurality of inwardly extending protuberances formed by a plurality of longitudinal and circumferential flutings, the protuberances defining a plurality of space resonant regions or cavities which in cooperation with the orbital motions of the electrons constitute efficient means for effecting transfer of energy therebetween.

For a better understanding of my invention,

reference may be had to the following description taken in connection with the accompanying drawing, and its scope will be pointed out in the appended claim. Fig. 1 of the accompanying drawing illustrates an embodiment of my invention as applied to an ultra high frequency magnetron wherein the space-resonant anode structure comprises a hollow or shell-like annular member, and Fig. 2 represents generally the path of the energy-delivering electrons within the electromagnetic field provided by the hollow anode member. Fig. 3 illustrates a further modification of my invention wherein the anode structure comprises a plurality of spaced metallic disks each of which includes a plurality of space resonant regions or cavities, and Fig. 4 is a plan view of one of the disk members shown in Fig. 3. Fig. 5 illustrates a still further modification of my invention wherein an annular anode member furnishes a plurality of space resonant regions formed by longitudinal and circumferential flutings.

Prior to a description of the various embodiments of my invention, it is believed that it may be helpful to review generally fundamental physical aspects relating to the operation of electric discharge devices of the magnetron type wherein there is provided an anode, a cathode, an electric field between the anode and the cathode, and a magnetic field at right angles to the electric field.

Due to the interaction of the electric and magnetic fields in devices of this nature, the electrons constituting the space charge between the anode and the cathode undergo both rotational and translational motion, that is rotational motion about the centrally located cathode and translational motion along the principal axis of the cathode. Neglecting the initial electron velocities at the cathode surface, and considering only planar movement, the electrons assume rotational and radial motions which produce a magnetic force substantially equal and opposite to the electric force acting thereon in the radial direction. Stated in other words and viewing the phenomenon from an acceleration standpoint, the net accelerating force upon each electron is equal to the difference between the applied electric force and the opposing magnetic force due to the radial and tangential motions of the electron.

The total kinetic or rotational energy of the electrons of the space charge may be analyzed as comprising two components; one is the energy due to motion along the radii, and the other is the tangential energy. I have found that in the prior art arrangements of magnetrons, the anode structure has imposed substantial limitations on the utilizations of the rotational energy of the electrons; that is, the prior art anode structures have been of such character that a substantial portion of the rotational energy of the electrons is not utilized because the electrons, just at the points or places in their orbital motions at which the electrons develop appreciable rotational energy, strike the opposing anode surfaces, thereby dissipating the energy at those surfaces in the form of heat rather than supplying the energy to the associated space resonant region.

In accordance with one feature of my invention, the electrons are intentionally afforded relatively large spiral or orbital paths extending into the electromagnetic field established by an electron-permeable or pervious anode structure wherein an appreciable part of the electron ro-

tational energy is utilized, and wherein the anode structure is of such size and configuration that a large percentage of the energy-delivering electrons do not come in contact with the anode structure until the electrons have delivered a substantial portion of their energy to the field.

Referring now to Fig. 1 of the accompanying drawing, I have there illustrated my invention as applied to an ultra high frequency magnetron including a plurality of enclosed electrodes which are positioned within an enclosing envelope such as a glass or vitreous envelope 1. The electrodes comprise a cathode, such as a cylindrical thermionic cathode 2, which may include a cylindrical or tubular metallic braid 3 coated with a suitable electron-emissive material and which is connected to an externally accessible terminal 4 through lead-in conductor 5 and a metallic strap 6. The cathode 2 also comprises an inner conductor (not shown) concentric with the cylindrical braid 3 terminated in a lead-in conductor 7 which extends to an externally accessible terminal 8. Lead-in conductors 5 and 7, are, of course, sealed to the bottom of container 1.

I provide an anode structure 9 which is electron-permeable or pervious to permit the travel of electrons constituting the space charge within the electromagnetic field defined thereby. The anode structure 4 may comprise a hollow anode member 9 which is shown broken away in Fig. 1, and may have a U-shaped cross section, the top part 10 and the bottom part 11 constituting transverse members for defining the electromagnetic field in the longitudinal direction. The anode member 9 is constructed of conductive material, preferably of a metal such as copper or brass, and may be provided with a plurality of longitudinal members 12 placed within the vicinity of the enlarged circular openings 13 and 14 in the top and bottom parts 10 and 11, respectively. Longitudinal members 12 may be employed for affording mechanical support and rigidity to the various parts of the anode member 9, or these members may also be employed to perform an additional function, namely an electrical function, to assist in the definition of the electromagnetic field pattern established within the anode member 9. Additional mechanical support for the hollow anode structure may be afforded by a plurality of radially extending vanes or rods 15 which extend from the longitudinal wall of the anode member 9 to the longitudinal supporting rods 12. Although my invention is not limited thereto, the rods 15 may also be employed for the purpose of assisting in the definition of the electromagnetic field patterns established within the anode member 9.

As a means for limiting the longitudinal movement of some of the electrons constituting the space charge of the device which tend to travel beyond the effective anode region, transverse disks 16 and 17 may be supported by the cathode structure 2 and may be placed appreciable distances from the top and bottom parts 10 and 11, respectively, of the anode member 9.

Electrical connections to the anode member 9 may be obtained by means of lead-in conductors 18 and 19 which are sealed in suitable tubulations at the top of the envelope 1 affording externally accessible members 20 and 21. If desired, only one such anode connection need be employed from an electrical standpoint, and in the embodiment of my invention illustrated the two lead-in conductors 18 and 19 also serve as mechanical means for supporting the anode mem-

ber 9 in desired space relation with the cathode structure 2. The entire device may be evacuated through a tubulation 22 which is sealed after the evacuation is accomplished.

A magnetic field is provided by employing an electromagnetic coil 23 surrounding that portion of the envelope 4 immediately opposite the anode part 9. The electromagnetic field so produced is substantially parallel to the longitudinal axis of the cathode structure 2.

As a means for supplying ultra high frequency energy to, or extracting ultra high frequency energy from, the anode region defined by member 9, I employ an electrode means which may take the form of a loop 25 extending into the anode part 9 and which is connected to insulated electrical conductors 25 and 26 which are sealed in a suitable glass press on the side of envelope 4. The press and conductors 25 and 26 may extend through an opening in coil 23.

Upon the application of a unidirectional voltage between the anode part 9 and the cathode structure 2, and upon proper energization of the coil 23, the electrons constituting the space charge will be given rotational motion. By the proper correlation of the magnetic field intensity, the electric field intensity and the anode field, the rotational motion of the electrons is sufficient to cause the electrons to traverse the interior region defined by the anode member 9.

The anode member 9 by virtue of its dimensions and configuration establishes a predetermined electromagnetic field pattern in accordance with its electromagnetic mode or modes of oscillation. These patterns of the electromagnetic field are, of course, determined by the radius of the anode part 9 and particularly the radius of the outside diameter thereof and the radii of the apertures or openings 13 and 14. From an elementary analysis point of view for the sake of obtaining a visual impression of the nature of the electromagnetic field patterns so established, it may be postulated that the circumferential distribution of the field at any one time comprises a plurality of segmental field sections such that adjacent segmental field sections are of opposite polarity. Of course, these polarities are not fixed but are continuously undergoing a time variation, such as a sinusoidal time variation. Although not limited to a structure wherein means are provided within the anode part 9, the longitudinal rods 12 and the radial rods 15 may be employed for the purpose of assisting in the definition of the electromagnetic field pattern.

By virtue of the electron-permeability of the anode member 9, the electrons constituting the space charge are given spiral paths having relatively large radii extending into the enclosed anode region of member 9 and there undergo cyclical variations in velocity to absorb energy from the magnetic field thereof, or to deliver energy thereto, depending upon the purpose for which the device as a whole is employed.

For example, when the device is employed for generating ultra high frequency electromagnetic waves, the electrons which pass into the anode region deliver energy to the electromagnetic field, and by virtue of the structure which permits substantial rotary motion with a minimum of structure for impeding such motion, a large portion of the rotational energy of the electrons is effectively utilized.

Referring now to the phenomenon by virtue of which energy may be extracted from the electrons constituting the space charge and delivered to the

electromagnetic field, it will of course be appreciated that electrons leave the cathode in all time phase relationships; that is to say, not all of the electrons which are emitted from the cathode are effective in transferring energy to the electromagnetic field of the anode part 9. More specifically, of course, only those electrons which leave the cathode and enter the electromagnetic field in a predetermined time relation with respect to the anode electromagnetic field are effective in delivering energy to the field. Generally speaking, it may be said that the electrons which leave the cathode and which enter the anode region at a time when the electric field, or the electromagnetic field for that particular region exerts an accelerating effect, absorb energy from the electromagnetic field. These electrons do not remain within the anode region for periods of time comparable to the periods of dwell for the energy-delivering electrons because the increased potential of the anode field during such time adds to the applied electric field, causing these electrons either to strike an anode part on the first outward trip or to return rapidly to the cathode within one cycle. On the other hand, the electrons which leave the cathode and enter the electromagnetic field at a time when the potential of the electromagnetic field exerts a decelerating effect thereon deliver energy to the field; that is, these electrons are slowed down in their motion, kinetic energy thereof being delivered to the electromagnetic field. Consequently these electrons remain within the anode region for substantially longer periods of time, and undergo successive or cyclic variations in velocity to deliver energy to the electromagnetic field. In other words, the aggregate effect of the energy-delivering electrons is greater than the effect of the electrons which absorb energy from the electromagnetic field.

In Fig. 2 there is diagrammatically illustrated a simplified plan view of the path of an energy-delivering electron which is emitted from the cathode cylinder 3 and which enters the hollow anode region, traversing or passing through the electromagnetic field thereof. For the purpose of simplification of this aspect of my invention, the anode structure has been shown as comprising only six segmental parts designating graphically three complete cyclic distributions of potential in which adjacent segments may be considered, for the purpose of elementary analysis, as comprising field sections of instantaneously different polarities. The dotted curve A indicates the probable mean path of an energy-delivering electron. The heavy curve B represents a probable path of an energy-delivering electron having rotational motion within the anode part 9, and at the same time undergoing radial changes in position incident to the interaction with the anode field.

In accordance with a still further feature of my invention, the dimensions of the anode part 9 may be correlated relative to the electron paths so that the energy-delivering electrons are outside the effective range of the anode region when sufficient energy, or a substantial portion of their energy, has been converted or extracted by the electromagnetic field. As the electrons deliver energy to the field, the phase position of the electrons relative to the instantaneous values of the high frequency field pattern advances in phase relative to the anode field, and this advance will continue to a point where the electrons would tend to absorb energy from the field unless the electrons are effectively removed from the anode

region. By the proper correlation of the dimensions of the anode part 9, the electrons which have spent the greater portion of their energy may be caused to pass outside the effective range of anode part 9. For example, the electrons may be made to impinge on the top, the bottom or side wall of the anode part 9.

Fig. 3 diagrammatically illustrates a modification of my invention wherein anode structure is provided which also permits utilization, in a large measure, of the rotational energy of the electrons in supplying energy to the electromagnetic field of a space resonant region or cavity. In this modification of my invention, I provide a plurality of wafer-like metallic disks 27-31 in alignment and which are maintained in desired axial displacement by means of a plurality of annular spacers 32. The complete anode structure may be assembled as a unit and held in position by means of a fixture 33 supported from the inside of an envelope 34 comprising the enclosure for an electric discharge device of the general type shown in Fig. 1.

Each of the disks 27-31 is provided with an enlarged central opening 35 in alignment with similar openings and through which the cathode cylinder 3 extends. A more detailed view of the disk construction may be obtained by referring to the plan view shown in Fig. 4 wherein the disk 27 is shown as comprising the enlarged central opening 35 in communication with a plurality of circumferentially spaced space-resonant regions or cavities which may take the form of a plurality of circular openings 36 in communication with the large central opening 35 by means of radial slots 37. Each of the openings 36 and its associated slot are dimensioned to be resonant to a particular frequency. These cavities may be viewed as affording the principal component of inductance by virtue of openings 36, and the capacitance component may be considered as being furnished primarily by the opposing surfaces of slots 37. Energy may be extracted from or supplied to the various space resonant regions by an electrode means which may take the form of a loop 38 extending into the opening and which comprises an extension of a concentric transmission line including a conductor 39 and an outer tubular conductor 40.

The operation of the embodiment of my invention illustrated in Figs. 3 and 4 is essentially the same as that explained above in connection with Fig. 1. In this modification of my invention, the anode structure is also designed to afford a small area or surface against which the electrons may impinge, thereby causing the electron space charge to lose only a relatively small amount of energy in the form of heat by impingement on the anode structure. Stated in other words, the spaces between disks 27-31, inclusive afford appreciable regions within which the electrons describe paths of relatively large radii, thereby delivering a substantial portion of the rotational energy to the electromagnetic fields of the various space resonant regions.

A still further embodiment of my invention is illustrated in Fig. 5 wherein anode structure, shown broken away, comprises an annular metallic cylinder 41 surrounding the cathode cylinder 3. The anode cylinder 41 is provided with a plurality of inwardly extending protuberances 42 defining therebetween a plurality of space resonant regions 43. The space resonant regions may be formed by a plurality of interconnected circumferential and longitudinal flutes or channels.

The modification of my invention shown in Fig. 5 also provides paths for the effective utilization of the energy incident to the electrons which describe paths of relatively large radii inasmuch as the electrons may traverse the channels between longitudinally displaced protuberances, delivering energy to the electromagnetic fields of the various space resonant regions.

While I have shown and described my invention as applied to particular devices, it will be obvious to those skilled in the art that changes and modifications may be made without departing from my invention, and I, therefore, aim in the appended claim to cover all such changes and modifications as fall within the true spirit and scope of my invention.

What I claim as new and desire to secure by Letters Patent of the United States is:

An electric discharge device of the magnetron type comprising an elongated cathode, an anode comprising a multi-cavity resonator surrounding said cathode and including a generally cylindrical conductive member, and a plurality of conductive structures electrically connected to and supported from said cylindrical member and extending radially inwardly in circumferentially spaced relation toward said cathode and terminating short of the cathode to define an inter-electrode space, said conductive structures defining substantial open spaces in a circumferential direction through which electrons may pass without being collected by said anode when moving within said anode under the action of a magnetic field substantially parallel to said cathode and a substantially radial electric field.
